UNITED STATES PATENT OFFICE

HEINRICH RENCK, OF HAMBURG, GERMANY

PROCESS FOR THE PRODUCTION OF PRINTING

Application filed December 22, 1928, Serial No. 328,057, and in Germany March 21, 1928.

In order to obtain any number of printed copies by means of plates manufactured in the manner previously known, the present invention has incorporated with it a mechanical device designed in such a way that, during the printing process, minute particles of metals with which the plates are coated are detached. These particles possess the property of precipitating exclusively in those places which are already covered with amalgam. The same result may also be achieved by mixing minute particles of the concentrated metal with the printing colour in such a manner that they are loosely composed with the latter. The effect is that, each time the ductor roller passes over the plate, the metal loosely mixed up with the printing colour precipitates in those places which are already covered with the amalgam, so that the separation of the metal from the colour takes place during the printing process. The metal is therefore continuously deposited on the die whilst printing goes on, the consequence being that that portion of the surface of the plate which is deprived of printing colour is raised above that portion of it to which this does not apply and that the quantity of colour distributed by the ductor roller is deposited in recesses. From these recesses the paper obtains a very much larger quantity of colouring matter, so that the results of the printing are improved. Moreover, the printing process itself is only made possible by the permanent addition of the metal during the printing. It has been proved beyond doubt that the coat of amalgam on the printing plate is destroyed in a very brief space of time if there is any break in the deposition of the metal which ought to go on uninterruptedly. Printing of large editions is quite out of the question in that way. The printing process is only made possible with the aid of the metal which must be added in minute particles.

The invention is illustrated in the accompanying drawings, in which:

Figure 1 is a sectional view illustrating the application of the picture to be printed and the application of the amalgam.

Figure 2 is a similar view of a slightly modified form.

Figure 3 is a similar view indicating the absence of amalgam between the portions of the picture to be inked for reproduction. 55

Figure 4 is a diagrammatic view showing the application of the finely divided amalgam to the printing rolls.

The present invention concerns the production of the so-called amalgam printing plates, that is, printing plates which, in contrast to the etched ones, that is, such printing plates as have deep and high lying portions, are completely flat upon the surface. Such amalgam printing plates may be substantially produced in two ways. 60

Upon a flat plate *a* consisting, for example, of brass, the picture to be printed is provided by means of any process, such as copying, screen or printing, etc. The plate *a* is then covered with a layer of amalgam, for example mercury amalgam. Thereby, those portions *b* which are covered by the picture portions prevent the adherence with the amalgam, whereas the free portions *c*, which therefore are not covered by picture surfaces, undergo a firm adherence with the amalgam. The surfaces *b* will take up printing ink, therefore, will act as printing elements, whereas the amalgamated surfaces *c* will repel the color and therefore not reproduce an impression. 75

Another form is shown in Figure 2. A flat plate *a* consisting, for example, of brass, is covered with a coating which consists of amalgam-repelling metal. This layer is *d*, and by way of example consists of nickel. The picture *e* to be printed is again produced upon this layer of nickel *d* by any process whatever. Then the plate *a*, with the nickel layer and the picture *e* which has been provided upon the layer of nickel *d*, is inserted into a galvanic bath. In this bath the nickel is removed from those places where it is not covered by the picture *e*, so that at these portions *f* (see Figure 3) the brass of the plate *a* becomes exposed. Then the plate is coated with amalgam and the amalgam adheres firmly to the plate *a* only at the portions *f*. These portions *f* then repel the color, while the pic- 80

ture surfaces *e* take up the color and operate as printing elements.

In such plates it is, however, necessary to renew the amalgamated portions *c* (see Figure 1) and/or the amalgamated portions *f* (see Figure 3) by adding mercury to the printing plates, whereby the amalgamation again becomes freshened.

This is not accomplished, however, by merely applying the mercury in metallic condition to the printing ink, but it is necessary that the mercury be applied in extremely finely divided form, that is, in atomized condition, to the color, however, not before the actual printing process but during the printing process. Therefore, the finely divided mercury is added to the color not in the color container, but to the color which is upon the rolls. However, upon the rolls the color lies in a very thin layer, and the mercury dust therefore cannot penetrate deeply into the color, because of its specific weight, inasmuch as only a thin layer of color is present, and furthermore the centrifugal force of the rotating rolls holds the mercury upon the surface, so that upon applying the color from the color roll to the printing plate, it is freely forced out between the color roll and printing plate, and can become placed upon the amalgamated portions and freshen them. The accompanying Figure 4 shows the rotary drum *g* of the printing machine upon which the printing plates *a* are clamped. *h* are the color rolls, to which for example the mercury is transferred in finely divided condition from a container *i*. At the points *h*, then the mercury dust held upon the surface of the rolls *h* will be forced off upon the printing plates *a*.

I claim:

1. A process for the purpose described wherein the mercury forming the ink-repelling material of the printing plate is continually renewed during the inking of the plate, consisting in applying the mercury in finely divided form to the printing ink while such ink is on the inking roll.

2. A process for the purpose described wherein the mercury forming the ink-repelling material of the printing plate is continually renewed during the inking of the plate, consisting in applying the mercury in finely divided form to the printing ink while such ink is on the inking roll.

In testimony whereof he affixes his signature.

55 HEINRICH RENCK.
